FARM GATE

Joseph Blake, Munday, Tex.

Application September 25, 1933, Serial No. 690,927

1 Claim. (Cl. 39—43)

This invention relates to a gate structure which is especially adapted for use on farms, and it has more particular reference to a type of gate adapted to be controlled from a distance on either side 5 of the gate by a simple pull of a lever cord.

Visualized from a slightly more specific viewpoint, it is to be pointed out that the assembly comprises a vertically swingable gate to extend across the roadway, said gate being mounted for 10 swinging on a horizontal axis and controlled by springs and weights to render it easy to operate, there being a pair of operating levers extending at right angles to the gate on opposite sides of said gate, so as to permit one lever to be actuated 15 when approaching the gate and the other lever to be actuated when leaving the gate so as to permit it to be raised and lowered by a person riding in an automobile without alighting.

Needless to say, I am aware of the fact that 20 gate structures of this general style are not new and, therefore, the present invention has to do with a structurally refined and improved arrangement characterized by requisite simplicity and durability and capable of fulfilling the requirements of an assembly of this type in a highly 25 practicable and satisfactory manner.

Other features and advantages will become more readily apparent from the following description and drawings.

30 In the drawings:—

Figure 1 is an end view of the complete assembly, showing the gate closed and illustrating its relationship with respect to the oppositely extending operating levers and supporting means there- 35 for.

Figure 2 is a top plan view of the structure shown in Figure 1.

Figure 3 is a side elevational view showing the gate closed in full lines and lifted to open position 40 in dotted lines.

Figure 4 is a fragmentary perspective view of the pivoted or anchored end portion of one embodiment of gate.

Figure 5 is a perspective view of a longitudinal 45 reciprocating type gate retaining latch.

Figure 6 is a detail sectional view on the plane of the line 6—6 of Figure 2.

Figure 7 is a detail sectional view of the gate post and latch keeper.

50 Figure 8 is a fragmentary detail elevational view of a lever supporting standard.

Attention is first invited to Figures 1 to 8 inclusive of the drawings. In Figure 3, the numeral 13 designates the gate. The frame of this may 55 be of horizontally elongated type and of any suit-

able construction and appropriately covered with wire (not shown) or made in any suitable manner. The gate frame includes among other parts an upright 14 having a guide bracket 15, as shown in Figure 6, which bracket is adapted to slidably 60 accommodate a reciprocating latch rod 16. This latch rod is adapted for cooperation with a keeper 17 on the gate post 18. The numeral 19 merely designates a stop collar and 20 an eye to which a return spring 21 is connected. The numeral 22 65 designates a pivotally mounted U-shaped adaptor or actuator element which is suspended on the frame bar 23 and connected with the latch rod by way of a pivoted link 24. The actuator 22 is controlled through the instrumentality of a flexible 70 cable or equivalent rod element 25 which may be conveniently differentiated as a connector. The gate is formed with a substantially triangular anchoring member at its pivoted end which embodies inclined bars 26 and a connecting bar 27 which 75 may be described as a fulcrum, this being mounted for oscillation in bearing eyes 28 mounted in the concrete supporting or anchoring block 29. The numeral 30 designates a return coiled spring and 31 a gate lifting spring which are both anchored on the block 29, the spring 31 being attached to the rear upright or member of the gate frame and the spring 30 to the lower member 80 of the frame.

The rear upright of the gate frame is formed 85 at its extreme upper end with a supplemental triangular frame 32 which constitutes a carrier for a counter-weight 33 held in desired adjusted position through the instrumentality of a set screw 34. This weight 33, together with the companion 90 spring 31, constitutes the means for facilitating swinging the gate, as a unit, on a horizontal axis and through a vertical arc from the full line position shown in Figure 3 to the dotted line position shown in the same figure against the tension 95 of the spring 30 when the latch rod 16 is released, and the gate set into motion.

The latch rod 16 may be released from either side of the gate by way of the actuating levers. Inasmuch as there are two of these levers and 100 they are located on opposite sides of the gate, I distinguish them as an outside lever 35 on the approach side of the gate and an inside lever 36 on the opposite or exit side. It is, of course, immaterial which side of the gate forms the approach and exit, but it is to be assumed that the gate is being approached from the roadway in the direction of the arrow A and the field or farm is being entered on the side indicated by the arrow B in Figure 1. Thus these two levers 35 and 110

36 are disposed at right angles to the pivoted end portion of the gate. Each lever is supported on a vertical standard 37 formed at its upper end with a fork 38 in which the intermediate portion 5 of the lever is pivotally mounted, as indicated at 39, the numeral 40 merely designating a stabilizing guide which works back and forth through the fingers of the fork to aid in insuring rigid operation of the lever. The free end of the lever 10 is provided with a pendent grasping or manipulating cord or equivalent element 41.

It follows that by entering the roadway on the side A of the gate and catching hold of the depending cord 41 and pulling it down, the lever 15 35, which is connected at its inner end to the pull cord 25, serves to release the latch rod 16 from the keeper 17 and to start the gate to lift. When this is accomplished, the spring 31 comes into action, setting the gate into motion and the spring, 20 aided by the counterbalancing weight 33, lifts the gate to complete open position, as shown by dotted lines in Figure 3. After the vehicle has been driven past the gate, the operator pulls upon the other cord 41, which causes the lever 36 and its 25 cable 25 to swing the gate to closed position, the spring 30 facilitating the closing movement of the gate. As before indicated, it is intended that the gate be operated by a person driving a vehicle and approaching the gate from either side, 30 this being accomplished without requiring said person to alight from the vehicle.

It is thought that the description taken in connection with the drawings will enable a clear understanding of the invention to be had. Therefore, a more lengthy description is thought unnecessary.

While the preferred embodiment of the inven-

tion has been shown and described, it is to be understood that minor changes coming within the field of invention claimed may be resorted to if desired.

I claim:—

A gate structure of the class described comprising a supporting member, a pair of spaced eye members extending upwardly therefrom, a gate having a cross rod connected at its center to the lower rear corner of the gate, said rod passing through the eyes of said members, a spring having one end connected to the rear of the supporting member and its other end to the rear upright member of the gate, a second spring having one end connected to the front edge of the supporting member and its other end to the lower member of the gate, a substantially triangular-shaped part having one corner connected with the upper rear corner of the gate, with one member of the triangular-shaped part forming an upper extension of the rear member of the gate and another part of the triangular-shaped part forming a rearwardly extending part of the upper member of the gate, and a third portion of the triangular-shaped part sloping downwardly and rearwardly, a weight adjustably connected to said diagonal or sloping part, a latch bar slidably supported by the gate, a substantially U-shaped member having the upper end of one limb pivoted to a part of the gate, a link connecting an intermediate part of said limb with the latch bar, and means connected with the other limb of the U-shaped member for operating the same, and exerting a pull on the gate from remote points.
